UNITED STATES PATENT OFFICE.

EDGAR PENNEY, OF WAYNESBOROUGH, PENNSYLVANIA.

COMPRESSOR-PUMP FOR REFRIGERATING APPARATUSES.

SPECIFICATION forming part of Letters Patent No. 363,672, dated May 24, 1887.

Application filed October 12, 1886. Serial No. 216,032. (No model.)

To all whom it may concern:

Be it known that I, EDGAR PENNEY, a citizen of the United States, residing at Waynesborough, in the county of Franklin and State 5 of Pennsylvania, have invented certain new and useful Improvements in Compressor-Pumps for Refrigerating-Machines; and I do hereby declare the following to be a full, clear, and exact description of the invention, such 10 as will enable others skilled in the art to which it appertains to make and use the same.

My invention relates to vertical compressor-pumps for refrigerating-machines.

Vertical compressor-pumps of this class 15 have heretofore been difficult of construction, by reason of the fact that the column or main frame was made of a single casting which was so large that it required extraordinary facilities for molding, casting, and finishing the 20 same.

One of the objects of my invention is to provide such a construction of the main frame of this class of pumps as to enable them to be constructed by the ordinary appliances of machine-shops and foundries, whereby the cost 25 of the same is greatly cheapened.

My invention consists in the peculiarities of construction hereinafter described, and particularly pointed out in the claims.

30 In the drawings, Figure 1 is an end elevation of a double compressor-pump embodying my improvements, partly in section. Fig. 2 is a plan of a single pump of the same character. Fig. 3 is a plan of a double compressor-pump, partly in section. Fig. 4 is an elevation, with parts in section, on line *x* *x* in Fig. 3.

The column or main frame of a single compressor-pump made in accordance with my 40 improvements is composed of two main parts, A A'. These parts are made larger at the base, as is usual in this form of devices, and are provided with exterior base-flanges, *a*, which are provided with suitable bolt-holes. 45 The bottoms of these parts are provided with dowels, which engage suitable openings in the foundation-girders A². These parts are also bolted to such girders and to anchor-plates embedded in the masonry-support. At the 50 base the inner sides of these castings are provided with flanges *F*, having perpendicular

faces *f*, and at the top they are provided with flanges F' F', which are connected by a web having a single face, *g*, as shown in Fig. 4. Between the upper and lower ends the parts A A' are provided with guides H for the cross-head slide. The faces of *g* and the face of the slides are all in the same plane or a direct line with each other. This construction permits the necessary planing of the parts A A' to be done in a speedy and economical manner.

Between the flanges F of the parts A A' are mounted the castings G, having bearing for the main operating-shaft, commonly called "pillow-blocks," and between the faces *g* *g*, at the upper end of A A', is mounted the pump-cylinder base I. The castings G are centered for the shaft, and are then planed from a center line to leave the bearing for the shaft exactly midway of the casting, so that these parts are interchangeable and reversible. The pump-base is finished in a like manner. These parts are connected securely to the parts A A', with which they come in contact, by strong bolts uniting the parts A A' into a single frame or column.

The part A' of the column is provided on its outer side with faces *e* *e*'. To the lower of these faces is secured the engine-bed E, with a cross-head guide, *e*, cast or bolted to the same. The upper cross-head guide, *e*', is attached to a separate girder connected at one end with the face *e* of the part A', and at the other end to the upper part of the engine-bed. The part A' of the column is provided with the opening K between the faces *e* *e*' for the passage of a link or connecting rod from the cross-head of the main shaft. In case of a single pump this main shaft is provided with a fly-wheel at one 90 or both extremities outside of the pillow-blocks, and is provided midway of its length with a crank receiving the link or connecting-rod of the pitman connecting with the cross-head of the engine, and a pitman connects to 95 a cross-head mounted on the slides H H for operating the pump.

The end of the engine-bed E is centrally bored for the passage of the piston, and the cylinder is bolted thereto in the usual manner. 100 The passage-way for the piston in the engine-bed, the guide thereon, and the guide on the

girder E' are centrally disposed upon such parts, so that there is no right or left hand to the engine construction.

When a double pump is required such additional pump is supported on a column or frame of two main parts, B B, which are of the same form as part A of the first-described frame or column, except that instead of having two flanges, F, one at each side of the base, they 5 may have such a flange at one side only. Between the flanges of the parts B B a pillow-block of the character described is placed and securely bolted in position. The main shaft is in this instance extended and given a bearing 15 in such block, and it is provided with a crank in the center of the column or frame, as already described.

It is found that a single bearing or pillow-block is sufficient for this additional pump; but 20 if preferred the parts B B can be made exactly like the part A, and two bearings or pillow-blocks employed. The column or frame B B is attached to the foundation girders A' in the same way as A A', and it is anchored in the 25 same manner. At the top the two columns are connected by the rods D with the pipe-ferrules D', inclosing the same between the columns.

If desired, more pumps constructed as just 30 described may be added to the structure.

It will be seen that by my construction the cumbersome parts of machines of this class are made in such divisions that they can be more easily cast and finished and their cost 35 greatly cheapened, while at the same time provision is made for securing such parts readily and securely together, forming a structure which possesses the requisite strength to withstand all working strains.

40 The pillow-blocks and pump-bases being made in the manner described, it will be seen that the parts are made in the most economical manner, and that there can be no difficulty when putting the parts together in securing 45 the proper alignment.

It will also be seen that the pump, whether single or double, is reversible, and can be readily made a right or left hand pump, as desired.

If desired, two compressor-pumps, as last described, may be employed, and a vertical engine to operate them be located between the two.

Parts A A' may be used as a frame for a vertical engine, in which case the part here designated as the pump-base would be made to form 55 the lower cylinder-head.

What I claim, and desire to secure by Letters Patent, is—

1. In a compressor-pump, a column or frame consisting of two main parts and intermediate 60 connecting parts, the attaching-faces at the top and bottom of the two main parts being at the same vertical plane, substantially as described.

2. The combination, with the two main parts A A', having attaching-faces at the top and 65 bottom in the same vertical plane, of pillow-block and pump-base, each centered and balanced, substantially as described.

3. A sectional standard of a compressor-pump frame or column formed with attaching-faces on one side, at the top and bottom, and between the two a guide the face of which and said attaching-faces are all in one plane, substantially as described.

4. The combination, with a compressor-pump 75 frame, of an engine bed connected thereto having a cross-head guide and a girder connecting the upper part of said engine-bed with the pump-frame and provided with a cross-head guide opposite the guide upon the engine-bed, 80 substantially as described.

5. The combination, with a compressor-pump frame, of an engine-bed attached thereto, and provided with a cross-head guide and a girder connecting the upper part of said bed, and the 85 pump-frame also provided with a cross-head guide, the said guides being centrally located on said parts, substantially as described.

In testimony whereof I affix my signature in presence of two witnesses.

EDGAR PENNEY.
